(57) **CLAIM**

The ornamental design for a fluorescent bulb holder, as shown and described.

DESCRIPTION

FIG. 1 is a perspective view of a fluorescent bulb holder showing my new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a bottom plan view thereof.

Broken lines are used to illustrate the environment of the claimed tool and form no part thereof.
